ATTORNEY.

UNITED STATES PATENT OFFICE.

SAMUEL W. ALSTON, OF PHILADELPHIA, PENNSYLVANIA, ASSIGNOR TO
JAMES LANNING, OF SAME PLACE.

GRATE.

SPECIFICATION forming part of Letters Patent No. 351,242, dated October 19, 1886.

Application filed September 26, 1885. Serial No. 178,285. (No model.)

To all whom it may concern:

Be it known that I, SAMUEL W. ALSTON, a citizen of the United States, residing in the city and county of Philadelphia, State of Pennsylvania, have invented a new and useful Improvement in Grates, which improvement is fully set forth in the following specification and accompanying drawings, in which—

Figure 1 represents a top or plan view of a grate embodying my invention. Fig. 2 represents a bottom plan view thereof. Fig. 3 represents a vertical section in line xx , Fig. 1. Fig. 4 represents a vertical section in line yy , Fig. 2.

Similar letters of reference indicate corresponding parts in the several figures.

My invention relates to improvements in grates; and it consists in the construction of the same with rocking bars mounted on a rotatable frame, as hereinafter fully set forth, whereby the said bars may be rocked simultaneously with the rotary movement of the frame.

It further consists in the combination of parts, arranged as herein described, whereby the grate may be readily dumped or tilted when desired.

Referring to the drawings, A represents a bed-plate, from whose front and rear depend hangers B, which are cast with or secured to said plate in any suitable manner.

C represents a bar, which is formed with journals C', the latter resting on the hangers B.

D represents the frame of the grate, from which depends a pivot, D', the latter being fitted in an opening in the bar C, whereby the frame may be turned horizontally or laterally on said bar, and as the bar is rotatably mounted on the hangers B, it permits the overturning of the grate, as will be hereinafter more fully described. The frame D is of the form of an open rim with a bar, D'', at the bottom, the pivot D' being connected with said bar. At the top of the frame are the grate-bars E, which are formed with journals E', which are mounted on said frame, it being seen that the bars are rotatable on the frame. Depending from the grate-bars are arms F F', which are connected at the bottom by an arm, G, which is pivoted to the arms F F', the arm F passing through

a slot, H, in the bar D'' of the frame D and a slot, J, in the rotary bar C.

To the front of the frame D is secured a rod, K, which passes through a guide, L, on the bed-plate, and has its outer end squared for attachment of a key or other suitable tool, by which the grate is raked.

To the side of the bed-plate is pivoted a lever, M, whose inner end or nose projects under the frame D and prevents overturning of the grate.

When it is desired to rake the fire, the frame D is rotated laterally by the key on the rod K, and as the arm F of the central grate-bar E strikes the wall of the slot J of the bar C said arm F is deflected laterally, thus imparting rocking motions to the connected grate-bar. As the arms F' of the other grate-bars are connected with the arm F by means of the arm G, rocking motions are also imparted to the remaining grate-bars, so that while the grate is rotated in horizontal directions each grate-bar is rotated or rocked, and so the fire is quickly and effectively raked.

By moving the lever M from the frame D and properly operating the rod K, the grate may be rotated with the journaled bar C, and thus overturned, so as to let down the fire or ashes into the ash-pit.

The side of the frame opposite to the lever M is provided with a bracket or hooked lug, M', for preventing lowering of the grate at said side.

Having thus described my invention, what I claim as new, and desire to secure by Letters Patent, is—

1. In combination with a central supporting-bar, a frame pivotally mounted thereon, and having a lateral extension forming a handle, oscillating bars mounted on said frame and provided with arms, and links connecting said arms, one or more of the arms of the oscillating bars engaging the supporting-bar, whereby the said bars may be operated by the lateral movement of the frame, substantially as described.

2. A frame having grate-bars rotatably mounted thereon, arms attached to said bars, a connecting-piece pivoted to said arms, a bed-plate, and a deflecting-piece mounted on said

- bed-plate, engaging one of said arms, substantially as described, whereby when the frame is moved the bars are carried with it and rotated or rocked thereon, as stated.
- 5 3. In a grate, a frame with rocking bars mounted thereon and provided with a pivot at the bottom thereof, in combination with a bed-plate, a bar furnishing a bearing for said pivot and sustained on said bed-plate, and devices connecting said rocking bars, consisting of arms attached to said rocking bars and links connected to said arms, one of said arms being in engagement with the said pivot-bearing bar, substantially as and for the purpose set forth.
- 10 4. A grate having a rotary raking frame, grate-bars rotatably mounted on said frame, a slotted bar to which the frame is pivoted, a bed-plate sustaining said slotted bar, and arms connected with the grate-bars and with each other, one of said arms passing through said slotted bar and being deflected thereby, causing the rocking of the grate-bars when the frame is rotated or moved, substantially as described.
- 15 5. A rotatable frame carrying rocking bars and formed with a bottom bar, D', which is provided with a pivot, D' and a slot, H, the bar
- C, receiving said pivot and having a slot, J, the bed-plate A, with hangers B, supporting said bar C, arms F F', attached to the grate-bars 30 and connected by a pivotal arm, G, one of said arms F F' passing through the slot J as a lateral deflector, substantially as stated.
6. A rotatable frame having rocking grate-bars with depending arms connected together, 35 a slotted bar mounted on the bed-plate and pivotally supporting said frame, one of the depending bars or arms passing through said slot, a bed-plate with guide, and a catch, all substantially as and for the purpose set forth. 40
7. The bed-plate A, with hangers B and guide L, in combination with bar C, having slot J, the frame D, with pivot D', having bearing in bar C, the bars E, journaled in the frame D, the arms F F', connected by the arms G, 45 said arm F passing through the slot J of the bar C, and the rod K, attached to the frame D, all substantially as and for the purpose set forth.

SAMUEL W. ALSTON.
